ELECTRICAL APPARATUS

Lee Devol and Richard A. Hartley, Penn Township, Allegheny County, Pa., assignors to The Union Switch & Signal Company, Swissvale, Pa., a corporation of Pennsylvania

Application December 2, 1938, Serial No. 243,620

2 Claims. (Cl. 178—44)

Our invention relates to electrical apparatus, and particularly to filters of the mechanically tuned type.

It is frequently desirable in electrical apparatus to cause an electroresponsive device to respond to electrical energy of one frequency only. The most commonly used means for achieving this result is a filter of the electromagnetic type. When such a filter is used for very low frequencies, however, it becomes cumbersome and has a tendency to lose its sharpness of tuning, that is to say, its ability to distinguish between frequencies differing from each other by only a small percentage.

It is generally known that a mechanically tuned vibrator is more sharply resonant than one stage of an electrical filter at the same frequency. Our present invention takes advantage of this fact to provide a filter which will be more highly selective than the usual electromagnetic filter with the same number of stages, or a filter that will produce equally good results with a simpler, less cumbersome and less expensive construction.

We shall describe two forms of electrical apparatus embodying our invention, and shall then point out the novel features thereof in claims.

In the accompanying drawing, Fig. 1 is a diagrammatic view showing one form of apparatus including a mechanically tuned filter embodying our invention. Fig. 2 is a view showing another form of apparatus including another form of mechanically tuned filter embodying our invention.

Similar reference characters refer to similar parts in both views.

Referring first to Fig. 1, the filter here illustrated, which filter is designated as a whole by the reference character F, is adapted to pass a single frequency only, and to operate over a wide range of impedances. The filter comprises a suitable source of magnetomotive force, here shown as a permanent magnet 3, the ends of which terminate in pole pieces 4 and 5 of high permeability ferromagnetic material. The pole pieces 4 and 5 are substantially C-shaped, and are arranged to provide two parallel air gaps 6 and 7 across which the flux from the permanent magnet passes in substantially equal amounts and in the same direction. Cooperating with the air gaps 6 and 7, respectively, are armatures 8 and 9 secured to one end of a spring reed 10, the other end of which is fastened to a fixed support 11. The filter also comprises a winding in the form of two coils 12 and 13 disposed on opposite legs of the pole

piece 4 and connected in series in such manner that currents flowing therein will set up additive fluxes in the pole pieces. The parts are so arranged and so proportioned that the reed 10 and associated armatures are mechanically tuned to vibrate at the single frequency which it is desired to have the filter pass, and that when the reed is vibrating, the vibration will not materially change the clearances between the armatures and the pole pieces.

With the filter constructed in this manner, whenever an alternating voltage is impressed across the coils 12 and 13, the resultant flux which is induced in the pole piece 4 will cause the flux density in the air gap 6 to increase and that in the air gap 7 to decrease during one-half of each cycle, whereas during the next half of each cycle the flux in the air gap 6 will decrease and that in the air gap 7 will increase. When the flux in the air gap 6 exceeds that in the air gap 7, the force exerted on the armature 8 tending to pull it into the field in the air gap 6 will exceed that on armature 9 tending to pull it into the field in the air gap 7, and when the flux in the air gap 7 exceeds that in the air gap 6, the force exerted on the armature 9 tending to pull it into the field in the air gap 7 will exceed that on armature 8 tending to pull it into the field in the air gap 6, with the result that the reed 10 will tend to vibrate. If the applied electromotive force is of the same frequency as that to which the reed and the associated armatures are tuned mechanically, the reed 10 will vibrate through a considerable amplitude, and will cause the permanent magnet flux threading coils 12 and 13 to vary in magnitude at the same frequency as the reed is vibrating, thereby generating a counter-electromotive force in these coils, and hence causing the coils to offer a relatively high impedance due to the motion of the reed. If, however, the frequency of the applied electromotive force is different from that to which the reed is tuned, there will be very little motion of the reed and associated armatures, and under these conditions, the impedance of the filter will be relatively low.

In the particular application of our invention shown in Fig. 1, the terminals of the coils 12 and 13 are connected across a load L which is supplied with variable frequency alternating current from a suitable source such as an alternator A through a series impedance I. With this arrangement, when the frequency of the current supplied by the alternator A is different

from that for which the filter is tuned, the low impedance offered by the filter will cause a relatively large voltage drop across the impedance I , and under these conditions the voltage impressed across the load will be insufficient to effectively operate it. When, however, the frequency of the current supplied by the alternator A is the same as that for which the filter is tuned, then the high impedance offered by the filter will cause less voltage drop across the impedance I , with the result that the voltage impressed across the load will rise to a value which is sufficient to effectively operate it.

One advantage of a filter constructed as shown in Fig. 1 is that it possesses an extremely sharp resonance, and is less cumbersome at low frequencies than the ordinary reactor-condenser combination for effecting the same result.

It should be pointed out that if the source A is of the type which has a limited output, by properly proportioning the parts the impedance I may be dispensed with.

Referring now to Fig. 2, the filter $F1$ here shown comprises two vibrating reeds 14 and 15 secured at one end to the opposite ends of the core 16 of an electromagnet E , the winding 17 of which is constantly supplied with direct current from a suitable source here shown as a battery B . The reeds 14 and 15 are mechanically tuned to vibrate at the resonant frequency at which it is desired to have the filter operate, and cooperate intermediate their ends with a core 18 of high permeability magnetizable material, and at their free ends with a core 19 , also of high permeability magnetizable material, sufficient air gaps being provided between the cores 18 and 19 and the reeds to prevent the reeds from striking the cores even when vibrating at their maximum amplitude. The core 18 is surrounded by an input winding 20 which is connected with the alternator A , and the core 19 is surrounded by an output winding 21 which is connected with the load L .

With the filter constructed in the manner shown in Fig. 2, the flux due to the electromagnet follows the path indicated by the long arrows, while the greater portion of the flux due to the alternating current supplied to the winding 18 follows the path indicated by the short arrows, it being obvious, of course, that this latter flux will tend to traverse this path in opposite directions during alternate half cycles. When the alternating flux is in the direction in which the short arrows are pointing, the alternating and permanent magnet fluxes will tend to add in the air gaps 22 and 23 between the core 18 and the reeds 14 and 15 , and, under these conditions, the reeds will be drawn toward each other more strongly than would be the case if the alternating flux were absent. When, however, the alternating flux is in the opposite direction to that in which the short arrows are pointing, the two fluxes will then tend to buck each other in the air gaps 22 and 23 , and, under these latter conditions, the reeds are attracted less strongly than would be the case if the alternating flux were absent. It will be seen, therefore, that when alternating current is being supplied to the winding 20 , the reeds 14 and 15 will tend to vibrate at the frequency of the alternating current, but that this vibration will be extremely small except when the frequency of the alternating current is equal to that for which the reeds are tuned. It will also be seen that when the reeds are vibrating, a cyclic variation will take place in the flux from the

electromagnet which traverses the core 19 , so that an alternating voltage will be induced in the winding 21 and will be supplied to the load L . In this connection it should be noted that since the electromagnet E has a high permeance and the magnetic circuit through the core 19 has a low permeance, when the reeds are not vibrating, substantially none of the alternating flux will thread core 19 , and hence no appreciable electromotive force will be generated in the winding 21 under these conditions.

Obviously a permanent magnet can be substituted for the electromagnet E in the filter $F1$ if desired, although this will result in lower values of operating flux and smaller amplitudes because of the lower permeance of permanent magnet materials.

Furthermore, since the windings 20 and 21 with the accompanying magnetic circuits are inductive, the advantages of electrical tuning in addition to mechanical tuning may be obtained in both the input and output circuits by connecting suitable condensers $C1$ and $C2$ in these circuits. As here shown, the condensers $C1$ and $C2$ are connected in parallel with their respective windings, but in some cases better results can be obtained with series tuning.

It will be obvious, of course, that the output of the filter $F1$ can be used to actuate a second similar filter etc. to provide as many stages as may be desired.

One advantage of a filter embodying our invention over the usual type of vibrating device is that there are no contacts which can become worn out and cause failure of the apparatus.

Although we have herein shown and described only two forms of electrical filters embodying our invention, it is understood that various changes and modifications may be made therein within the scope of the appended claims without departing from the spirit and scope of our invention.

Having thus described our invention, what we claim is:

1. An electrical filter comprising means for creating a unidirectional magnetic field which normally divides between two parallel paths each including an air gap, two magnetically independent armatures secured to a cantilever reed and cooperating with said two air gaps respectively, said reed and said armatures being tuned mechanically to vibrate at a particular frequency, and a winding associated with said two paths and effective when supplied with alternating current to cause the flux to alternately vary in said two air gaps, whereby said winding will offer a relatively high impedance to alternating current having a frequency corresponding to that to which said reed is tuned and a relatively low impedance to alternating current of any other frequency.

2. An electrical filter comprising a permanent magnet, two pole pieces secured to the ends of said permanent magnet and forming two parallel magnetic paths each including an air gap, a pair of magnetically independent armatures secured to a vibratory cantilever reed and cooperating with said two air gaps, said reed and said armatures being tuned mechanically to vibrate at a particular frequency, and a winding disposed on one of said pole pieces and effective when supplied with alternating current to alternately vary the flux traversing said air gaps.
